PROPELLER

Anthony Assala, Des Moines, Iowa

Application February 11, 1935, Serial No. 5,925

5 Claims. (Cl. 170—172)

This invention relates to propellers and more specifically to air propellers as used in the airplane art and may be considered as an improvement on the propeller disclosed in my issued 5 Patent No. 1,519,102, under date of December 16, 1924.

The principal object of my invention is to provide a propeller that tends to eliminate the usual "slippage" at the outer end portions of 10 the blades which, as is well known, seriously reduces the efficiency of the propeller.

A further object of this invention is to provide a highly efficient propeller for airplanes, dirigibles, and like that is not only of one-piece construction, but one that has no mechanism or individual moving parts.

A still further object of my invention is to provide a propeller construction that draws the air or like medium inwardly and rearwardly to 20 and through the hub portion of the propeller, and then casts the same laterally back of the main radial blades of the propeller.

A still further object of my invention is to provide a propeller having both main radial wing 25 blades and hub blade members that is so constructed that the hub blade members extend to positions both in advance and rear of the radial blades.

A still further object of my invention is to 30 provide a combination hub and radially bladed propeller that is refined in appearance, durable in use, and economical in manufacture.

These and other objects will be apparent to those skilled in the art.

35 My invention consists in the construction, arrangement and combination of the various parts of the device, whereby the objects contemplated are attained as hereinafter more fully set forth, pointed out in my claims and illustrated in the 40 accompanying drawing, in which:

Fig. 1 is a front view of my propeller designed to rotate counterclockwise ready for use.

Fig. 2 is a rear view of my propeller and illustrates the fact that the back of the hub portion 45 has no air passageways extending through it.

Fig. 3 is a side view of the hub portion of my propeller.

Fig. 4 is a cross-sectional view of the hub portion of my propeller, taken on line 4—4 of 50 Fig. 3.

Fig. 5 is a side view of my propeller with the radial blades cut away and is taken at a right angle to that of the view shown in Fig. 3.

Although my propeller disclosed in my heretofore referred to issued patent was highly efficient

and desirable, it did have certain objections which have been overcome in my present propeller. I enumerate the objections as follows: Firstly, its hub portion was not properly stream-lined; secondly, the hub blade elements did not continuously extend from front to the rear air exits in the hub portion; and thirdly, and most important of all, the air passing through the hub portion was not cast out directly laterally and radially of the hub portion and to points directly 10 back of the main wing blades. In other words, while my previous propeller had its rear end hub portion open, my new herein described propeller is completely closed.

The overcoming of these objections in my previous propeller by my present propeller will readily be hereinafter understood and which I will now describe:

Referring to the drawing, I have used the numeral 10 to generally designate the hub portion 20 of my propeller. Extending from the periphery of this hub portion are the usual two oppositely disposed radial main wing blades 11 and 12, as shown in Fig. 1. The relatively small centrally located hub blades herebefore referred to are in reality the mere construction of the hub 10 in which are spiral passageways 14 and 15, which may be considered with the hub shell as of turbine construction. This hub 10, which is of the nature of a turbine, is stream-lined by having its front 30 bullet-shaped, as shown in Fig. 1 and Fig. 5. The back surface of the hub is flat and has no opening communicating with the passageways 14 and 15. These passageways have their forward 35 ends communicating with the outside atmosphere at diametrically opposite positions on each side of the central hub shaft attaching sleeve 13, respectively. These openings of these passageways are each of elongated slot construction and extend from a point adjacent the center of the 40 hub to a point near the root of the leading edge of the main radial blade adjacent to it, as shown in Fig. 1. As the plane of the leading edge of each of the blades cuts a line in advance of the center point of the hub these openings of the 45 passageways, while being radially disposed, are, however, not longitudinally arranged as to the blades 11 and 12, but are disposed at angles thereto. These passageways 14 and 15 of the turbine 50 constructed hub extend rearwardly and outwardly in oppositely arranged spiral paths, as shown by dotted lines in Fig. 2; the walls of the passageways performing the function of the hub blades.

Each passageway has its rear end communicating with the outside atmosphere near the back 55

side of the hub in the form of an elongated slot, as shown in the drawing. Each of these outlet slot openings of the passageways 14 and 15 are comparatively long by extending substantially 5 one-quarter around the rear side periphery of the hub. As the passageways 14 and 15 extend concentrically relative to each other and in opposite spiral directions radially through the hub portion, the passageway 14 will terminate under 10 and in advance of the blade 12, while the passageway 15 which has its entrance adjacent the blade 12, will terminate under and in advance of the main blade 11. As the slot exit openings of the 15 passageways are in the periphery of the hub, any medium passing through and out of the passageways will be cast directly radially from the hub and back and under the main blades 11 and 12. This feature is very important for several reasons. If the passageways instead terminated so as to 20 cast the medium directly to the rear and such a propeller were on the shaft of a motor the medium would not only be obstructed in its flow by the motor, but would have a tendency to back up, seriously interfering with the efficiency of the 25 hub portion of the propeller and the passage of new medium through the hub. Furthermore, the air or medium passing through the hub portion would not be directed outwardly and at a right angle to its original flow back of the main 30 blades and for the increasing of their efficiency. Still further, the hub portion would take care of a considerable amount of air directly in front of it, but would not do much in the aiding of the main blades in pulling the propeller through the 35 medium. On the other hand, by having the exit openings of the passageways terminating around the rear portion of the periphery of the hub, such as shown in the drawing, the air passing through the hub will be dissipated radially and in the rear 40 of the propeller and not be affected by the motor or other parts positioned in the rear of the propeller.

Also, it will be noted that the passageways extending rearwardly and outwardly in spiral formation, will take advantage of the movement of the medium by centrifugal forces and by the time 45 the medium passes from the exits of the passageways it will be directed outwardly at a right angle to its original direction of flow. This changing 50 of the direction of the flow of the medium passing through the hub will provide desired power to the propeller and will be in addition to that obtained by the main blades 11 and 12. Of course, my hub construction takes care of the medium 55 directly in front of the same, which, without my construction, would have to move to the side of the hub in order to pass the propeller. This movement of the medium to the side of the propeller hub aids in the undesirable "slip" of the 60 main propeller blades as it starts the air or medium radially before the main blades reach it. This only provokes the outward movement of the medium at the time the same is engaged by the main propeller blades, due to the fact that 65 the main propeller blades themselves tend to move the medium not only rearwardly, but outwardly by centrifugal forces. It is for this reason that the extreme tips of propeller blades are indeed very inefficient. However, by my hub construction, the air is not only taken care of that 70 is directly in front of the hub, but considerable adjacent air is taken care of, thereby causing the medium in front of the complete propeller to move inwardly and rearwardly instead of outwardly and rearwardly as in an ordinary type 75

propeller. This inward and rearward movement of the air in front of my entire propeller for increasing the efficiency of the main blades 11 and 12 is accomplished by the walls of the passageways 14 and 15 extending at a greater pitch than that of the pitch of the main propeller blades. Also, I have provided integral cup ears 16 and 17 on the front of the hub portion and adjacent the two passageways 14 and 15, respectively, as shown in the drawing. 5

These ear cup portions, which may be considered as a mere continuation of the outer wall of each of the passageways have their leading edges resting in a plane in advance of the leading edges of the main propeller blades, as shown in Fig. 3. 15 These cup portions 16 and 17 extend from near the portion 13 of the hub to the leading edge of the main blade adjacent to them and preferably to points just slightly beyond the plane of the periphery of the chief hub portion 10, as shown 20 in Fig. 1.

One of the greatest advantages, however, of the air passing through the hub being cast laterally back of the main blades is the building up 25 of a more dense medium directly adjacent the rear sides of the main blades, thereby increasing the efficiency of the main blades from this standpoint. Also, this medium which is cast at substantially a right angle to the movement of the air initially contacted by the main blades, gives 30 more resistance to the rearward movement of the air contacted by the main blades, thereby further increasing the efficiency of the main blades. It therefore will readily be seen that I 35 increase the efficiency of the main blades by affecting the air both in front of the main blades and in the rear of the main blades.

As the propeller rotates very rapidly it is desirable that the leading edge of the exit of each 40 of the passageways be in advance of the leading edges of the main blades, respectively, in order that the radially cast medium will be directly back of each blade. The cup ears 16 and 17 contact the air in front of the hub in the same manner as blades and guide the medium into the passageways. The member 13 is to facilitate the 45 connection of the propeller to a shaft, but if the complete propeller be of metal, merely a hole through the center of the hub portion may be provided for the reception of a shaft.

The walls of the passageways also terminate in the rear of the trailing edges of the main blades 50 in order that the air therefrom will be cast properly back of the main blades.

Although I have described my invention as 55 particularly adapted to the airplane or like industry, it may be used to equal advantage wherever an efficient propeller is desired. Its efficiency is substantially the same in any medium and may be used as a stationary positioned propeller 60 or one that is desired to travel through a comparatively still medium such as that experienced by airplane propellers.

Some changes may be made in the construction and arrangement of my improved propeller 65 without departing from the real spirit and purpose of my invention, and it is my intention to cover by my claims any modified forms of structure or use of mechanical equivalents which may be reasonably included within their scope. 70

I claim:

1. In a propeller, a hub portion having a solid back and an opening extending into said back for the reception of a shaft, two blades extending from said hub portion, and two spiral passage- 75

ways extending in opposite directions radially through said hub portion each having its forward end communicating with the front of said hub and its rearward end communicating with the peripheral side of said hub and in close proximity to the solid back portion of said hub portion.

5. 2. In a propeller, a hub portion, blades extending radially from said hub portion, and two spiral passageways extending through said hub portion in opposite directions radially from each other and terminating at points on the periphery of said hub portion.

10. 3. In a propeller, a hub portion, blades extending from said hub portion, two spiral passageways extending through said hub portion, and cup ear portions on the front of said hub portion for guiding a medium into and through said passageways.

15. 4. In a propeller, a hub portion, blades extending from said hub portion, and spiral passage-

ways extending in opposite directions radially through said hub portion each having its forward end communicating with the front of said hub portion and its rear end communicating with the periphery of said hub portion; the walls of said 5 passageways extending beyond the leading edges of said blades.

10. 5. In a propeller, a hub portion, blades extending from said hub portion, and spiral passageways extending in opposite directions radially through said hub portion each having its forward end communicating with the front of said hub portion and its rear end communicating with the periphery of said hub portion; the walls of said 15 passageways extending beyond the leading edges of said blades and rearwardly of the trailing edges of said blades.

ANTHONY ASSALA.
